WEATHERPROOFING STRUCTURE

Filed Jan. 31, 1927

INVENTOR

David H Harnly

By *Charles W. Wells* Atty

UNITED STATES PATENT OFFICE.

DAVID H. HARNLY, OF CHICAGO, ILLINOIS.

WEATHERPROOFING STRUCTURE.

Application filed January 31, 1927. Serial No. 164,721.

This invention relates to a weather proofing structure for windows or the like and primarily consists in means for clamping the weather strip in position and excluding the weather therefrom.

The invention comprises the novel structure and combination of parts hereinafter described and more particularly pointed out and defined in the appended claims.

10 In the accompanying drawings which illustrate certain preferred embodiments of this invention and in which similar reference numerals refer to similar features in the different views:

15 On the drawings:

Figure 1 is a sectional view through a window showing an application of this invention.

Figure 2 is a transverse sectional view 20 taken upon the line II-II of Figure 1.

Figure 3 is a fragmentary and exaggerated sectional view taken substantially upon the line III-III of Figure 2 with parts in elevation.

25 Figure 4 is a transverse sectional view similar to Figure 2 illustrating a slight modification of the invention.

As shown on the drawings:

This invention has been illustrated in con-

30 nection with a sliding window having a lower rail 1 and upper rail 2 and lateral stiles 3. The window stiles fit in suitable guideways 4 in the window frame for guiding the window in its opening and closing movements as is well known in the art.

35 This invention concerns itself with means for excluding the weather from entering between the stiles 3 and the guideways 4. In the present instance, the means are illustrated only in connection with one side of the window and it will of course be understood that the same will be duplicated upon the other side of the window.

The weather proofing means for excluding

40 the weather between the stiles and the guideways consists of a felt strip 5 which is partly encased by a sheath 6. This sheath fits over the outer margin of the strip and encases substantially half of the width of the strip. The

45 window stile is provided with a groove 7 in one side which tapers gradually from the top to the bottom, being deeper at the bottom than at the top. The front margin of the weather strip 5 is adapted to fit in this groove.

50 It will be clearly patent that on account of the slope of the groove the weather strip will

more tightly fit against the window when the latter is in closed position and prevent rattling and vibrations and thuswise eliminating the springs now commonly used. At 60 the same time the slope of the groove allows the window to be more easily opened.

It will be noted that the groove 7 is made substantially in alignment with the plane of the window frame 8 in order that the weather strip may be positioned upon the window frame when in use. In order to maintain the weather strip 5 in such position, there has been provided a retaining shield 9 (Figure 2) which is co-extensive with the weather 70 strip and which has its outer margin secured by screws 10 or the like to the window frame. This retaining shield 9 has an outwardly offset portion 9^a just in advance of the attaching margin. This outwardly offset portion 75 9^a extends over the encased portion of the weather strip 5 and has a downward bend as indicated at 9^b for gripping the weather strip preferably adjacent the end of the sheath 6. From the bend 9^b, the retaining shield has an 80 outwardly directed weather flange 9^c that is adapted to be positioned adjacent or closely adjacent the window stile as shown in Figure 2 to protect the weather strip 5 from the weather.

85 In the modification shown in Figure 4, there is a retaining shield 11 which is also attached at its outer margin by a row of screws 10. This shield 11 has an outer offset portion 11^a that fits over the encased portion of 90 the weather strip proper and a downwardly bent portion which provides a bead 11^b for gripping the weather strip just in advance of the sheath 6. This retaining shield differs from the one shown in Figure 2 in that the 95 weather flange 11^c is formed to fit in a small groove 12 in the side of the window stile to more effectively exclude the weather from the weather strip proper 5.

95 It will be appreciated that this weather 100 proofing structure can readily be applied to steel railway cars having metal window frames or to office buildings having metal window frames, as well as any structures involving wooden window frames. It will also 105 be appreciated that the retaining shield effectively retains the weather strip in place against buckling or distortion or crumbling so that its effective relation with the window stile is not impaired in use. It will also be 110 appreciated that the weather flange on the retaining shield excludes the weather from

the weather strip proper and serves to preserve the same from damage by the weather.

I am aware that many changes may be made and numerous details of construction 5 may be varied through a wide range without departing from the principles of this invention and I, therefore, do not purpose limiting the patent granted hereon, otherwise than necessitated by the prior art.

10 I claim as my invention:

1. In a weather proofing structure for windows and the like, the combination with a window frame, of a window having stiles 15 slideable in said frame, one of said stiles having a groove in its side, a weather strip positioned on the window frame and engaging said groove and a retaining shield secured to the window frame and fitting over a portion of said weather strip for securing the same in 20 position, said retaining shield having a weather flange extending along the window stile to exclude the weather.

2. A weather proofing structure for a window comprising a strip of felt partially 25 encased, a support for said strip, a retaining shield attached to said support and fitting over a portion of said weather strip and having a weather flange directed outwardly for the purpose set forth.

30 3. In a weather proofing structure for windows or the like, a partially encased fabric strip, a support therefor and a retaining shield attached to said support and having an outwardly offset portion fitting over a portion 35 of said strip and having a gripping bead for gripping said strip and an outwardly directed weather flange for excluding weather from said strip.

40 4. In a weather proofing structure for windows and the like, the combination with a window frame, of a window having stiles slideable in said frame, one of said stiles having a tapering groove, a weather strip upon the window frame extending into said groove 45 and a retaining shield secured to said frame

and superposed on said weather strip for retaining the same in position.

5. In a weather proofing structure for windows or the like, a window frame, a window having lateral stiles slideable in said frame, a 50 weather strip secured to said frame and engaging one of said stiles for excluding the weather and a retaining shield attached to the window frame and having an outwardly offset portion engaging over a portion of said 55 weather strip and having a bead in gripping engagement with said weather strip and a weather flange extending along the window stile for the purpose set forth.

6. In a weather proofing structure for windows or the like, a window frame, a window having lateral stiles slideable in said frame, a weather strip secured upon said frame for engaging one of said stiles for excluding 60 weather between said stile and frame, a retaining shield attached to said frame and having an offset portion engaging over a portion 65 of said weather strip and having a bead at the end of said offset portion for gripping engagement with said weather strip and a weather flange extending outwardly along the window stile, said weather flange and window having inter-engaging parts.

7. In a weather proofing structure for windows or the like, a window frame, a window 75 having lateral stiles slideable in said frame, a fabric strip upon the window frame for engaging said stile, a retaining shield secured to said frame and having an offset portion 80 engaging over a portion of said weather strip and having a bead at the end of said offset portion for gripping said weather strip and a weather flange extending outwardly along said stile, said stile having a groove and said 85 weather flange having a lip extending into said groove for the purpose set forth.

In testimony whereof I have hereunto subscribed my name.

DAVID H. HARNLY.
